(57) **CLAIM**

The ornamental design for a headlight for a vehicle as shown and described.

DESCRIPTION

FIG. 1 is a right, front perspective view of a first embodiment of a headlight for a vehicle according to the design; FIG. 2 is a front view thereof; FIG. 3 is a right side view thereof; and FIG. 4 is a top view thereof.

FIG. 5 is a left, front perspective view of a second embodiment of the headlight for a vehicle according to the design; FIG. 6 is a front view thereof;

FIG. 7 is a left side view thereof; and,

FIG. 8 is a top view thereof.

The broken lines in the drawings depict portions of the headlight for a vehicle and form no part of the claimed design. The additional broken lines in the drawings illustrate environmental subject matter only and form no part of the claimed design. Also enclosed is a set of photographs of an embodiment of the design.

1 Claim, 8 Drawing Sheets
